DUOPNEUMATIC HANDLE FOR AIR-METHOD CLEANERS

Daniel Benson Replogle, Berkeley, Calif., assignor to The Ohio Citizens Trust Company, as trustee, Toledo, Ohio, a corporation of Ohio

Application August 12, 1936, Serial No. 95,609

10 Claims. (Cl. 15—9)

The invention relates to cleaning apparatus and more particularly to portable electric suction cleaners of the air-method type wherein air may be drawn from either of two different sources according to the position of a valve carried by the cleaner.

One of the objects of the invention is to improve and simplify the operation of the valve.

Another object is to improve and simplify the construction of the casing which houses the power plant and air filtering apparatus.

Another object is to provide means whereby the flow of dust may be more conveniently observed by the operator of the cleaning apparatus.

Other objects and advantages will be apparent from the further detailed description and the accompanying drawings in which is set forth for purposes of illustration, a specific embodiment of the inventive thought.

In the drawings:

Fig. 1 is a side elevation of a cleaner embodying my invention.

Fig. 2 is a view partly in elevation and partly in section showing the upper portion of the cleaner including the means for operating the valve from a movable portion of the handle.

Fig. 3 is a view looking down on the valve cap parts being shown in plan and parts in section.

Fig. 4 is a section on the line 4—4 of Fig. 2.

Fig. 5 is a side elevation of the upper portion of the cleaner from a different angle from that shown in Fig. 2, the swinging handle grip being shown in two different positions.

Fig. 6 is a perspective view looking down on the top of the cleaner as the same would be viewed by the operator.

Fig. 7 is a fragmentary side elevation of the upper portion of the cleaner showing the bag partly removed.

Fig. 8 is a perspective view showing the cleaner used in inverted position.

Fig. 9 is a side view showing the cleaner supported in upright position by a wall bracket.

Fig. 10 is a detail showing a link for operating the controlling valve.

The cleaner comprises in general a body portion A which includes suction producing and air filtering means together with the housing therefor, and a valve B adapted to control the direction of the dust laden air into the body portion from a swinging handle section C or from a fixed pipe section D which may be connected to a floor tool, according to the angular position of the pipe section C.

The body portion A comprises a caddy, casing

or barrel 10 which houses the suction producing and air filtering means. This housing may be composed of hard fiber or of plastic material such as Bakelite or may be formed of light metal such as aluminum. However a non-conducting material is preferred and according to the specific embodiment of the invention herein set forth it is intended that hard fiber be utilized. As shown the caddy includes sections 11 and 12 housing the power plant and the filtering means respectively and a top member 13 in the form of a ring or chime having openings which communicate with pipe sections C and D.

The ends of the member 12 are shown as expanded and fitted over the members 11 and 13. 15 Where fiber is employed this may be accomplished by first soaking and thereby expanding the ends of the fiber tube 12 after which the same is allowed to dry and contract over the adjacent sections as set forth in my application 10 Serial No. 586,192 filed January 12, 1932, now Patent No. 2,142,149.

At a suitable location above the power plant, preferably at the junction between sections 11 and 12 a hinged and collapsible support 14 is 25 shown attached to the caddy, such support being provided with rollers 15. This support may be of the type disclosed and specifically claimed in my application Serial No. 94,653 filed August 6, 1936.

Within the section 11 the suction producing means or power plant is housed. This may be of the multiple unit type which includes two or more motors preferably operating in opposite directions about their common axis and one or more fans driven by each motor, a convenient arrangement being disclosed in my application Serial No. 64,420 filed February 17, 1936, now Patent No. 2,175,641.

The lower end of the caddy is preferably closed by a cap 16 having lateral outlets 17 each of which is sufficient to carry the entire output. Either may be plugged and a blower pipe attached to the other. The outlets are preferably of the same size so that the plug employed may be interchangeable.

Current is supplied to the power plant by means of a conductor cord 18 carried by the caddy and provided with extensions for connecting the same to a wall plug, or other suitable source of current.

The dust collector within the section 12 may be of any suitable type. Preferably it comprises an inner bag 19 composed of porous paper which may be removed when fouled and replaced by another bag. The inner bag may be supplemented and reinforced by an outer bag 20 which remains with

the caddy and which is preferably composed of relatively coarse mesh material such as cloth, wire, netting, matting or the like the purpose of which is to permit air to freely pass therethrough but to prevent direct contact between the inner bag and the wall of the caddy.

The sections 11 and 12 may be separable if desired or may be secured together. Where they are separable the interior of both sections is readily accessible.

The chime ring 13 is provided with two inlets 21 and 22 communicating with the suction pipes C and D respectively. Within the ring 13 is mounted the removable and rotatable valve cap member B. This cap includes a funnel 23 having a reduced neck 24 to which the mouth of the cleaner bag 19 may be detachably secured as by a rubber band, string, spring or like flexible element. The funnel is provided with a side opening 25 to communicate with opening 21 or 22 of the ring or chime 13 according to the angular position of the valve cap of which the funnel forms a part.

The valve likewise preferably includes a transparent top 26 through which the operator may look and observe the quantity of dust entering the cleaner. The valve or cap with the cleaner bag attached may be removed to permit replacement of the bag where a paper bag is employed or to permit emptying of the bag where a cloth bag is used. The valve is shown partially removed in Fig. 7.

The function of the transparent top is to permit the operator to see the character of the material which is being drawn into the cleaner and to determine the quantity of dust entering the same. Consequently it is of importance that this cap should be visible at all times and close to the eye of the operator. For this purpose it is located at the top of the body member and it is one of the features of the present invention that the handle portion of the cleaner is so arranged as not to obstruct the visibility of the transparent top.

According to my invention improved means are provided for moving the valve to communicate with the pipe sections C or D according to the angular position of the movable section C. Any suitable means may be employed for this purpose according to the broadest aspects of my invention.

As shown an arm 27 is pivoted to the ring 13 at a position opposite the point where the rotatable pipe C enters, both being rotatable about the same axis, as best illustrated in Fig. 2. This arm is connected to the pipe C by means of a clamp 28. The arm 27 is connected to the valve member 23 through a curved link 29 shown in detail in Fig. 10, which is connected to the arm 27 through a ball and socket connection 30 and to the member 23 through a pin 31 carried by the valve member and extending through an opening 32 in the enlarged end 33 of the link.

On the outside of the ring 13 is carried a member 34 having a curved slot 35 in which the end 33 of the link rides as the handle C and arm 27 are swung to and fro. A guide member 36 preferably resilient, is provided for the pin 31, said guide forming the slot 37 between the guide and top of the member 34.

At one end of slot 35 there is provided a release notch 38, normally closed by a spring catch 39 which catch may be retracted to allow removal of the link 29 from the pin 31 when it is desired

to take off the valve cap, as when the cleaning bag is to be removed.

A fiber extension 40 may be fitted over the swinging portion of the handle C and held air-tight by contraction as previously described with reference to the parts of the caddy 10. Suitable extension devices such as flexible hose and furniture dusting tools or the like, may be attached to the movable handle to permit cleaning of walls, furniture and the like.

The pipe D is shown as curved so that its lower end will be at the upper portion of the cap 16. This pipe fits into a socket 44 at the lower end and extension section 45 is also connected to the socket to which section the floor tool 46 may be detachably secured, such tool being of any desired type as for example that shown in my Patent No. 1,994,868 dated March 19, 1935.

In operation the fan motor or motors are started and dust laden air is drawn into the air filter through either pipe C or pipe D according to the angular position of the movable section C, the movement of this handle being transmitted to the valve B through the arm 27 and link 29. The member C also serves as a handle for propelling the apparatus to and fro across the floor. Owing to the lightness of the apparatus it may be inverted as illustrated in Fig. 8 and the section C applied to the floor or a suitable floor tool may be applied to this section.

The cleaner may also be supported in upright position to function as a semi-permanent system as illustrated in Fig. 9. The cleaner may be supported by hose pipe hanger 50 such as shown in my Patent No. 1,884,870 dated October 25, 1932, such hanger carrying a connector member 51 to which a hose extension 52 carrying the furniture dusting tool 53 may be attached.

The invention has been described in detail for the purpose of illustration but it will be apparent that variations and modifications may be resorted to as will be apparent to those skilled in the art, without departing from the inventive thought involved.

I claim:

1. A portable suction cleaner including a cylindrical container enclosing suction producing means at one end and air filtering means at the other, a rotatable valve assembly serving as a cap covering the air filtering end of the container, a suction pipe carried by and fixed with reference to the cylindrical container, and another suction pipe carried by the container and movable with reference thereto, both pipes being outside the container and connectible to cleaning tools, and each adapted to be selectively placed in communication with the air filtering means according to the position of said valve assembly, and means connecting the movable pipe section and said valve assembly for actuating the valve when the movable section is actuated.

2. A suction cleaner as set forth in claim 1, wherein the valve assembly and the air filtering means are removable as a unit.

3. A suction cleaner as set forth in claim 1, wherein the suction pipes communicate with openings in a rim at the top of the cylindrical container, within which rim the valve assembly fits.

4. In a suction cleaner, a housing containing air filtering means communicating with a source of suction, a pair of suction pipe sections carried by the housing, one being movable and the other fixed with reference to the housing, and both being outside the housing but adapted to be

placed in communication therewith, and a rotatable valve assembly covering the air filtering end of the housing connected to and movable by actuation of the movable pipe section to selectively place one or the other of said pipe sections in communication with the source of suction.

5. In a suction cleaner, a housing containing air filtering means communicating with a source of suction, a rotatable valve assembly covering the inlet end of said housing, a pair of suction pipe sections both carried by and external to said housing, one being movable and connected to the valve assembly for rotating the same, said pipe sections being adapted to be selectively placed in communication with the air filtering means according to the position of the valve assembly.

10. In a suction cleaner, a housing for air filtering means, having a pair of suction inlets, a pair of suction pipe sections external to said housing communicating with said inlets, and each connectible to cleaning tools, one section being movable, and a valve assembly serving as a cap for said housing, actuated by said movable pipe section and selectively controlling said inlets.

15. In a suction cleaner, a tubular housing for air filtering means, having a pair of radial inlets adjacent the air filtering means for admitting dust laden air from different sources, and a valve member within the end of said tubular housing for controlling the direction of flow of air into the tube, the air filtering means being secured to the valve assembly and removable therewith as a unit.

20. In a suction cleaner, a tubular housing for air filtering means having a pair of radial inlets for admitting dust laden air from different

sources, a pair of suction pipe sections external to said housing and communicating with said inlets, each being connectible to cleaning tools and one being movable with reference to the tubular housing, and a valve assembly fitting 5 within the air filtering end of the housing for controlling said inlets, said valve assembly being connected to and actuated by said movable pipe section.

9. In a suction cleaner, a tubular body having 10 a pair of openings within the chime thereof, air filtering means housed within said body member, suction producing means communicating with said air filtering means, and a rotatable transparent topped valve cap assembly for the air inlet 15 end of said body member, said assembly including a ring portion fitting within the chime of the body member, and having an opening therein adapted to be placed in communication with either of said chime openings, one of said pipes 20 being movable, and means actuated by movement of said movable pipe for rotating said valve assembly.

10. A suction cleaner including a cylindrical container enclosing suction producing means at 25 one end and air filtering means at the other, a rotatable cap covering the air filtering end of the container, a fixed suction pipe and a movable suction pipe, both pipes being outside the container and connectible to cleaning tools, and each 30 adapted to be selectively placed in communication with the air filtering means according to the position of said cap, means connecting the movable pipe section and said cap and a floor tool connected to the fixed suction pipe. 35

DANIEL BENSON REPLOGLE.
